R. B. Gorsuch,

Steam Pump.

U. S. 12,625.

Patented Apr. 3, 1855.

UNITED STATES PATENT OFFICE.

ROBERT B. GORSUCH, OF NEW YORK, N. Y.

DIRECT-ACTING HYDRAULIC STEAM-PUMP.

Specification of Letters Patent No. 12,625, dated April 3, 1855.

To all whom it may concern:

Be it known that I, ROBERT B. GORSUCH, of the city, county, and State of New York, have invented a new and useful Improvement 5 in Direct Double-Acting Steam-Pumps; and I do hereby declare that the following is a full, clear, and exact description of the same, reference being had to the annexed drawings, making a part of this specification, in which—

Figure 1, is a vertical section of my improved pump the plane of section being through the water and steam valves and passages. Fig. 2, is an external view of ditto 15 in elevation, a portion of the outer casing of the pump being removed. Fig. 3, is a horizontal section of ditto, (x) (x) Fig. 1, being the line of section. Fig. 4, is a detached vertical section of the pump chamber. Figs. 5 and 6, are detached views of 20 the packing ring. Figs. 7 and 8, are detached views of the plunger.

Similar letters of reference indicate corresponding parts in the several figures.

This invention relates to a new and useful improvement in direct double acting steam pumps and consists in admitting water under pressure, into the suction ends of the pump cylinder as will be hereafter shown, 25 whereby the steam is assisted in throwing the steam valve, an easy motion given the force and suction valves, and the blow or concussion attending the working of the plunger in ordinary pumps at the commencement of each stroke avoided.

To enable others skilled in the art to fully understand and construct my invention, I will proceed to describe it.

A, Figs. 1 and 2, represents a steam cylinder, and B, Fig. 1, is a piston which works therein; C is the piston rod and D is the steam valve of the cylinder A. The above parts are in common use and require no particular description.

E, Figs. 1 and 2, is the outer casing of the pump, having a stuffing box F at its upper end through which the piston rod C works, G is the pump cylinder within the casing E and having corrugated or crimped 45 plates H connected to its upper and lower ends. These plates H are also connected to the upper and lower ends of the casing E leaving a chamber or space I between the casing and cylinder at one side with which 50 a suction pipe J communicates and a chamber or space I' at the opposite side with

which an eduction or force pipe L communicates see Fig. 1. On the corrugated plates H there are valves (a) (a') the valves (a) at one side of the pump cylinder G opening 60 inward, and the valves (a') at the opposite side opening outward.

M is a plunger attached to the lower end of the piston rod C, and D' is a packing ring placed within the pump cylinder G, the 65 plunger working snugly within the ring, see Fig. 1. The packing ring D' has apertures (b) through it, four are shown in Fig. 3, two are seen in Fig. 1 at opposite sides of the plunger, and only one is seen in Fig. 6. 70

N is a circular opening in the pump cylinder G with which a pipe O is connected, see Figs. 2, 3 and 4. This pipe O is provided with a valve P as shown in Fig. 2, and said pipe may communicate with the 75 "main" or any reservoir having a sufficient head of water to give the water in the pipe O a requisite amount of pressure.

Q is the rod of the steam valve D having stops (c) (c) upon it and R is an arm attached to the piston rod C, the outer end of the arm working on the valve rod Q and between the stops (c) (c) see Figs. 1 and 2.

Operation: The plunger M is moved up and down by the action of the steam upon 80 the piston B in the cylinder A in the usual manner. When the plunger M is forced downward in the pump cylinder G the water underneath the plunger, which was drawn up during the upward movement of the 85 plunger, is forced through the valves (a') into the space I' and out of the force or eduction pipe L the suction valves (a) on the opposite side of course being closed by the pressure of the water against them, 90 meanwhile as the plunger descends, the valves (a) above the plunger are opened by the suction or vacuum formed by the descent of the plunger the water from the pipe J rushing into the cylinder above the plunger 100 and the opposite valves (a') are closed, see arrows, Fig. 1. When the plunger moves upward in the pump cylinder, the position of the valves (a) (a') are reversed, the valves (a) above the plunger being closed by 105 the pressure of the water, and the valves (a') opened and the water forced out through the pipe L. This action will be readily understood as it is common to all double acting pumps. In the ordinary 110 pumps there is inevitably a vacuous space in the suction end of the chamber at the com-

pletion of each stroke, more or less, according to the speed of the pump and height of suction, which vacuous space is passed through by the returning plunger at a 5 greatly accelerated speed, checked instantaneously by the water, thereby badly straining the machine. Pumps driven by a crank motion and regulated by a balance wheel are not so much affected by this difficulty as 10 direct acting pumps, where a constant fluid resistance is depended upon for a regular motion.

The above difficulty is remedied by my improvement as follows: When the plunger 15 has nearly reached the end of a stroke, see Fig. 1, in which the plunger is nearly down, the upper end of the plunger will pass the holes or openings (b) in the ring packing D and the water under pressure in the pipe 20 O will rush through the openings (b) over the plunger and into the suction end of the pump cylinder, and will not only prevent or destroy the vacuum but will also act suddenly upon the forcing end of the plunger 25 with a power equal to, or approaching that upon the forcing end of the plunger; this water pressure acting conjointly with the steam at the moment the engine is taxed to move the steam valves in addition to its 30 regular load enables it, by means of the arm R on the piston rod C to throw the steam valve D with unerring precision across the openings, and at the same time, the water from the forcing end of the pump-chamber 35 having been driven through the forces valves (a'), the motion of the plunger has not been accelerated to such a degree but that the reversing takes place quietly. The returning plunger immediately closes the openings (b) 40 in the ring packing D, and cuts off the communication with the pipe O until it reaches

the point in the upward stroke corresponding with the one represented in Fig. 1.

The charging of the pump chamber as specified above, does not decrease the effective result of the engine, as, the water ejected merely fills the space which must otherwise necessarily remain unoccupied when the plunger reverses. The water pressure therefore, subserves a treble purpose, that of assisting the steam in throwing the steam valve, of easing the action of the force and suction valves (a) (a') and also of filling the otherwise vacuous space in the pump chamber and preventing entirely the blow 50 or concussion above alluded to.

My improvement as herein specified admits of a perfect adjustment of the water pressure to the speed of the pump by means of the valve P in pipe O, as shown in Fig. 2. 60

Having thus described my invention, what I claim as new and desire to secure by Letters Patent, is—

Effecting a water pressure upon the suction end of the pump plunger M in direct- 65 acting steam pumps, at, or near the completion of the stroke, without diminishing the resistance against the forcing end of the plunger, in the manner as herein shown or in an equivalent way, for the purpose of closing the suction valves (a) filling the vacuous space in the pump chamber, preparing the force valves for opening, and acting conjointly with the steam pressure upon the piston B whereby the steam valve D is operated with precision whatever may be its 70 velocity.

R. B. GORSUCH.
